UNITED STATES PATENT OFFICE.

PETER ERMATINGER, OF OSHKOSH, WISCONSIN, ASSIGNOR TO NICKOLAS BLAKE, OF OSHKOSH, WISCONSIN.

JAR HOLDER.

Application filed December 17, 1926. Serial No. 155,487.

My invention relates to household utensils and has particular reference to improvements in fruit jar holders, my purpose being to provide a simple, inexpensive device 5 which is efficient for holding a fruit jar to permit a cover therefor to be readily removed therefrom or applied thereto, and which is adjustable to accommodate jars of different sizes.

With the foregoing and other purposes in view, my invention consists in the novel features of construction, combination and arrangement of parts as will be hereinafter more fully described, illustrated in the accompanying drawings and defined in the appended claims.

In the drawings, wherein like characters of reference denote corresponding parts in the different views:

Fig. 1 is a perspective view of a fruit jar holder embodying the novel and essential features of my invention; and

Fig. 2, a plan view of same.

Referring to the drawings in detail, it will be observed that my improved jar holder includes essentially a band A formed preferably from a length of metal rod half-round in cross section and composed of two substantially semi-circular sections 10 and 12, 25 pivotally connected together at adjacent ends as at 14, the opposite or free end portions 16, 16 of said sections being straight and extending substantially radially from the band, thereby to provide a pair of handle members 30 for swinging the sections towards or away from one another about their pivotal connection 14 to contract or expand the band.

The flat faces of the sections 10 and 12 are disposed inwardly, and secured in any 40 suitable manner to or against the inner flat face of each of said sections, near their pivotal connection 14, is a pad 18 of any suitable yieldable material, such as rubber, adapted to engage a jar when the band A is contracted or clamped about the same to 45 frictionally resist turning movement of the jar within the band without danger of breakage of the jar.

Detachably and adjustably connectible 50 with the band A and adapted for cooperation with the pads 18 to grip a jar disposed within the band is a pair of clips 20, 20 which are duplicates of one another whereby they may be used interchangeably and which are 55 adapted to be positioned on the sections 10,

12, respectively, adjacent to the handles 16 and spaced approximately ninety degrees from the pads 18, respectively.

The clips 20, 20, being duplicates of one another, only one of them will be described in detail. It is formed from a single strip of sheet metal of slightly greater width than the material of the band A and of suitable thickness to impart the necessary stiffness thereto. The strip is bent into U-shape as 65 shown and thus comprises a pair of spaced parallel sides 22, 22 connected together at one end of the clip by a transverse bight portion 24, which latter has suitably secured against its outer face a pad 26 of rubber or 70 other yieldable material. A series of recesses is provided in each side 22, the recesses of the two sides being arranged in aligned pairs and the different pairs being spaced longitudinally of the clip. Three pairs of 75 recesses are illustrated in this instance, designated 28, 30 and 32, respectively, the pair 28 being nearest the bight portion 26, the pair 32 being farthest from said bight portion and the pair 30 being between the other 80 two pairs. The recesses open through corresponding edges of their respective sides 22, so that the clip may be engaged with the band A, with the latter engaged in any selected pair of recesses, simply by movement 85 of the clip transversely with respect to the band.

Since the band A in this instance is half-round in cross section, the wall of each recess nearest the bight portion 26 of the clip 90 is straight, while the wall thereof remote from the bight portion is curved as shown, so that when the clip is engaged with the band the straight and curved walls of the recesses will engage snugly against the inner and outer faces of the band, respectively, to hold the clip solidly assembled with the band. Of course, the band A is not necessarily half-round in cross section and if it is formed from material of any other cross section the recesses in the clips will be shaped to correspond to the cross section of the band.

The clips 20, 20 are adapted to be engaged 105 with the sections 10, 12 of the band, respectively, near the handles 16, so that they will be spaced substantially equal distances from each other and from the pads 18. If a jar of large diameter is to be gripped the clips will be placed on the band with the 110

latter engaged in the recesses 28, so that the inner ends of the clips equipped with the pads 26 will extend only a minimum distance within the band, but if a jar of smaller diameter is to be gripped the clips will be placed on the band with the latter engaged either in the recesses 30 or 32, so that the inner ends of the clips will extend a greater distance within the band.

10 A loop 34 slidable along the handles 16 provides means for maintaining the holder clamped upon a jar.

Although the clips 20 in the present instance are shown as being provided with 15 three pairs of recesses, this number obviously may be increased or decreased as desired. Furthermore, clips such as those indicated at 20, 20 may be used in lieu of the pads 18. I find, however, that the use of 20 two pads 18 and two clips 20 provides a very satisfactory arrangement, especially when the clips are provided with a series of three recesses, as these provide for all necessary adjustments of the clips to enable 25 the holder to grip a relatively wide range of different sized jars.

From the foregoing description considered in connection with the accompanying drawings, it is believed that the construction, operation and advantages of my invention will 30

be clearly understood. I desire to point out, however, that various changes and desirable additions may be made in and to the same within its spirit and scope as defined in the appended claims.

35

I claim:

1. A jar holder comprising an expandable and contractible band adapted to embrace a jar, and clips detachably and adjustably engageable with said band for frictionally 40 gripping a jar embraced by the latter, said clips each having a series of recesses in which the band is selectively engageable to dispose gripping portions of the clips greater or less distances from the center of 45 the band.

2. A jar holder comprising an expandable and contractible band adapted to embrace a jar, and clips detachably engageable with said band for gripping a jar embraced by 50 the latter, said clips each being formed from a single length of sheet metal bent into U-shape to provide spaced parallel sides and an end portion connecting them, said sides being provided with aligned pairs of recesses 55 spaced longitudinally of the sides to receive the band.

In testimony whereof I hereunto affix my signature.

PETER ERMATINGER.
